UNITED STATES PATENT OFFICE.

LANE JOHNSON, OF INGRAM, AND RICHARD W. MOSES, OF PITTSBURGH, PENNSYLVANIA, ASSIGNORS TO UNITED ENGINEERING AND FOUNDRY COMPANY, OF PITTSBURGH, PENNSYLVANIA, A CORPORATION OF PENNSYLVANIA.

CORRUGATING MACHINE.

Application filed May 25, 1923. Serial No. 641,404.

To all whom it may concern:

Be it known that we, LANE JOHNSON and RICHARD W. Moses, citizens of the United States, residing at Ingram and Pittsburgh, respectively, county of Allegheny, and State of Pennsylvania, have invented a new and useful Improvement in Corrugating Machines, of which the following is a full, clear, and exact description.

10 The present invention relates to the metal-working art, and more particularly to means for corrugating sheet material.

It is customary in the metal-working art to corrugate sheet material by passing the same between a pair of corrugating rolls having means for feeding one sheet to the rolls during each revolution thereof. Usually the length of the sheets to be corrugated is only a fraction of the circumferential length of the corrugating rolls, it being desirable to use rolls of relatively large diameters. The output of a corrugating mechanism of this character is therefore considerably less than the capacity of the corrugating rolls. By the present invention, we have provided a corrugating machine having means for feeding a plurality of sheets in succession to the corrugating rolls during each revolution thereof, thereby providing a machine having a materially greater output than machines of this character as heretofore constructed. Another feature of the invention is the provision of an open-backed roll housing for facilitating the removal of the rolls therefrom.

35 In the accompanying drawings, there is shown, for purposes of illustration only, one embodiment of the present invention, it being understood that the drawings do not define the limits of the invention, as changes 40 may be made in the construction and operation therein disclosed without departing from the spirit of the invention or scope of our broader claims.

In the drawings:

45 Figure 1 is a front elevation of the corrugating machine,

Fig. 2 is an end elevation of the machine,

Fig. 3 is a vertical sectional view taken on the line III—III of Fig. 1,

50 Fig. 4 is a detail view of a portion of the feeding mechanism,

Fig. 5 is a sectional view taken on the line V—V of Fig. 4,

Fig. 6 is a plan view of the feed table, and

Fig. 7 is a sectional view of a portion of a corrugated sheet.

Referring to the drawings, the reference character A designates a housing which is open at its back except for a pair of vertical bolts 2, each of which is pivoted at its lower end to the base of the housing A by means of a pivot pin 3 extending through an eye 4 formed on the lower end of the bolt. The bolts 2 form one side of the windows in the end frames of the housing and in which are arranged the bearing blocks 5 of a pair of corrugating rolls 6 and 7. The rolls are maintained the desired distance apart by adjustable wedges 8. Each of the bearing blocks of the upper roll 6 is engaged by a screw 9 operated by a handle 10 and provided with a lock nut 10', said screws preventing separation of the corrugating rolls.

The rolls are driven in unison by a motor 11 mounted on top of the housing A, said motor having a gear 12 on the shaft thereof meshing with a gear 13 on a horizontal shaft 14. The shaft 14 has a bevel gear 15 on each end thereof meshing with similar bevel gears 16 on the upper ends of vertically extending worm shafts 17 and 18. The worm shaft 17 has a worm 19 in driving engagement with a worm wheel 20 mounted upon one end of the upper roll 6, and the worm shaft 18 has a worm 21 in driving engagement with a worm wheel (not shown) on the opposite end of the lower roll 7.

With the construction above described, when it is desired to remove one of the rolls from the housing, it is merely necessary to loosen the nuts 22 on the screw-threaded upper ends of the bolts 2 and swing the latter downwardly and outwardly, and then place a skid in position to receive the roll and roll said roll bodily from the housing.

For feeding sheets to the rolls in the desired relation, there is provided a feeding mechanism comprising an inclined feed table 23 supported in front of the rolls by means of suitable braces 24 rigidly secured at one end to the base of the housing A, and

at the other end to the under side of the table adjacent the front thereof. The table 23 has downwardly directed flanges 25 and 26 along the front and rear edges thereof. Extending through these flanges and supported thereby are a plurality of parallel guide rods 27, which extend at right angles to the axis of the corrugating rolls, and parallel to and spaced slightly from the under side of the table 23. Each guide rod 27 has a reduced threaded end 28 extending through an opening in the flange 26 and a nut 29 on said screw-threaded end for clamping said flange between said nut and the shoulder on the rod at the base of the screw-threaded end thereof, whereby said rods are held rigidly in position. Slidably mounted upon each guide rod 27 is a block 30 extending through and arranged to reciprocate in an elongated slot 31 in the table 23. The upper surfaces of the blocks 30 are substantially flush with but slightly above the upper surface of the inclined table 23, and a narrow plate or bar 32 is fastened upon said upper surfaces of said blocks by screws 33, said plate or bar extending longitudinally of the table 23 and parallel to the axes of the rolls. A plurality of curved guide fingers 34 are secured to the flange 25 and extend upwardly and over the front portion of the table to guide the sheets delivered to the table, so that said sheets will drop upon the table in front of the plate or bar 32 when the latter is in the retracted position shown in the drawings.

Means is provided for reciprocating the plate or bar 32 and comprises a gear 35 mounted on one end of the lower roll 7, and meshing with a pinion 36 suitably supported in the housing A. A rock-shaft 37 is journaled in the base of the housing A and extends parallel to the axes of the rolls. The rock-shaft 37 has secured to one end thereof a rocker-arm 38 connected by a link 39 with a crank-arm 40 actuated by the pinion 36. Certain of the blocks 30 have a pair of integral spaced arms 41 extending downwardly therefrom and having a pin 42 journaled therein, said arms straddling the end of a link 43 having said pin extending therethrough. Each link 43 is pivotally connected at its opposite end to the end of a rocker-arm 44 carried by the rock-shaft 37. Each link 43 is made in two parts, one part being of channel form and having an elongated slot 45 therein, through which bolts 46, carried by the other part, extend for clamping the parts together in adjusted position. The adjustable links 43 afford means whereby to slightly advance or retard the time of entering of the leading edge of each sheet between the bite of the rolls to thereby insure the commencement

of the corrugating action always at the proper point.

The ratio between the gear 35 and pinion 36 is such as to cause the reciprocation of the bar 32 a plurality of times during each revolution of the corrugating rolls. With this construction, therefore, it is possible to corrugate a plurality of sheets for each revolution of the rolls. For example, assuming a roll diameter of two feet and a sheet width of twenty-four inches, three sheets could be corrugated per revolution of the rolls. It will be apparent that the driving connections disclosed between the lower roll and the reciprocating bar 32 enable said bar to be actuated in timed relation to the operation of the rolls, whereby the sheets may be delivered to the rolls at the proper speed, and the leading edge of each sheet entered between the bite of the rolls at exactly the proper time.

The advantages of the present invention arise from the provision in combination with corrugating rolls of means for automatically feeding a plurality of sheets to the rolls during each revolution of the latter, and from the provision of an open-backed housing for facilitating the removal of the rolls from the housing.

We claim:

1. In apparatus for corrugating sheet material, a pair of corrugating rolls, means for driving said rolls, and automatic means for feeding sheets to said rolls, comprising a stationary feed table for supporting the sheets while being advanced to the rolls, means movable above said table for engaging each sheet and advancing the same on said table to said rolls, and means for actuating said movable means, substantially as described.

2. In apparatus for corrugating sheet material, a pair of corrugating rolls, means for driving said rolls, and automatic means for feeding sheets to said rolls, comprising a stationary feed table for supporting the sheets while being advanced to the rolls, means movable above said table for engaging each sheet and advancing the same on said table to said rolls, and means operated by one of said rolls for actuating said movable means, substantially as described.

3. In apparatus for corrugating sheet material, a pair of corrugating rolls, means for driving said rolls, and automatic means for feeding sheets to said rolls, comprising a stationary feed table for supporting the sheets while being advanced to the rolls, a bar extending longitudinally of said table above the same for engaging and moving each sheet on said table towards said rolls, and means actuated by one of said rolls for reciprocating said bar over said table, substantially as described.

4. In apparatus for corrugating sheet material, a pair of corrugating rolls, means for driving said rolls, and automatic means for feeding sheets to said rolls, comprising a feed table, a bar extending longitudinally of said table above the same for engaging and moving each sheet towards said rolls, guide rods arranged beneath said table, means carried by said bar and slidably engaging said 10 guide rods, said means extending through slots in said table, and means connected to said bar for reciprocating the same over said table, substantially as described.
5. In apparatus for corrugating sheet material, a pair of corrugating rolls, means for driving said rolls, and automatic means for feeding sheets to said rolls, comprising a feed table, a bar extending longitudinally of said table above the same for engaging 15 and moving each sheet towards said rolls, guide rods arranged beneath said table, means carried by said bar and slidably engaging said guide rods, said means extending through slots in said table, a rock-shaft, 20 driving connections between said rock-shaft and one of said rolls, and adjustable means connecting said rock-shaft to said bar, whereby to reciprocate said bar above said table, substantially as described.
- 25

and one of said rolls, and means connecting said rock-shaft to said bar, whereby to reciprocate said bar above said table, substantially as described.

6. In apparatus for corrugating sheet material, a pair of corrugating rolls, means for driving said rolls, and automatic means for feeding sheets to said rolls, comprising a feed table, a bar extending longitudinally of said table above the same for engaging 30 and moving each sheet towards said rolls, guide rods arranged beneath said table, means carried by said bar and slidably engaging said guide rods, said means extending through slots in said table, a rock-shaft, 35 driving connections between said rock-shaft and one of said rolls, and adjustable means connecting said rock-shaft to said bar, whereby to reciprocate said bar above said table, substantially as described.

40
45
In testimony whereof we have hereunto set our hands.

LANE JOHNSON.
RICHARD W. MOSES.
